United States Patent Office

Des. 204,226
Patented Apr. 5, 1966

204,226

WINTER HAT

Marine Dewey Bogart, 36 Bay View Road,
Wellesley, Mass.

Filed May 3, 1965, Ser. No. 85,083

Term of patent 3½ years

(Cl. D3—13)

Fig. 4.

Fig. 5.

Fig. 6.

FIG. 1 is a side elevation of a winter hat, showing my design;

FIG. 2 is a front elevation thereof;

FIG. 3 is a rear elevation thereof; and

FIGS. 4, 5 and 6 are sections on lines 4—4, 5—5 and 6—6, respectively, of FIG. 1.

I claim:

The ornamental design for a winter hat, substantially as shown.
